(57) **CLAIM**

The ornamental design for a vehicle charger, as shown and described.

DESCRIPTION

FIG. 1 is a front elevation view of a vehicle charger embodying our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a bottom, front, and right side perspective view thereof.

The broken lines in the drawings illustrate portions of the vehicle charger that form no part of the claimed design.
